UNITED STATES PATENT OFFICE.

LEWIS S. KEIM, OF BAKERSFIELD, CALIFORNIA.

CURTAIN-STRETCHER.

1,286,340.

Specification of Letters Patent. Patented Dec. 3, 1918.

Application filed March 26, 1917, Serial No. 157,525. Renewed October 4, 1918. Serial No. 256,919.

To all whom it may concern:

Be it known that I, LEWIS S. KEIM, a citizen of the United States, residing at Bakersfield, in the county of Kern and State of California, have invented certain new and useful Improvements in Curtain-Stretchers, of which the following is a specification.

This invention relates to improvements in curtain stretchers.

10 The main object of the invention is to provide a simply constructed, foldable stretcher of this character which may be easily and quickly set up and knocked down and folded compactly for shipping, storage 15 or other purposes.

Another object is to provide simple and efficient means for supporting and holding the rods on which the hooks are strung.

With the foregoing and other objects in view, which will appear as the description proceeds, the invention resides in the combination and arrangement of parts and in the details of construction hereinafter described and claimed, it being understood 25 that changes in the precise embodiment of the invention herein disclosed may be made within the scope of what is claimed without departing from the spirit of the invention.

In the accompanying drawings:

30 Figure 1 represents a top plan view of a stretcher constructed in accordance with this invention ready for use,

Fig. 2 is a detail bottom plan view thereof,

Fig. 3 is a transverse section taken on the 35 line 3—3 of Fig. 1, and

Fig. 4 is an end elevation of one of the rails.

In the embodiment illustrated, side rails 1, end rails 10, pivot rods 15 and hooks 20, 40 are shown.

The side rails 1 are made in sections 2 hingedly connected at 3. It is to be understood that any desired number of these sections may be employed, three being here 45 shown, of equal length, one end section being hinged to the middle section to fold in one direction and the other end section thereof hinged to fold in the opposite direction as is shown clearly in Figs. 1 and 2.

50 The end rails 10 are similarly constructed except that they are here shown made of two instead of three sections.

Each of the rails is provided with a longitudinally extending groove 4, the side walls 55 of which are undercut as shown at 5 and are adapted to receive blocks 6 shaped to fit

said grooves and which are designed to form seats for the pivot rods 15 which are mounted in the grooves 4. These pivot rods 15 are of considerably less diameter than 60 the width of the grooves 4 so that the hooks 20 which are strung on said rods may have ample room for turning thereon to engage and disengage them from the curtains to be stretched. Any desired number of hooks 20 65 may be strung on these rods (about two hundred being usually used for curtains of ordinary lengths and widths, although obviously any desired number may be employed, they being preferably spaced about an inch or an 70 inch and a half apart when applied).

The pivot rods 15 are secured in their seats by means of screws 7, said rods being shown made in sections corresponding in length to the length of the sections of the 75 rails to which they are applied, and the screws 7 are shown extending through the opposite ends of said rod sections whereby they are reliably secured in position when the rails are folded. The side rails 1 which 80 are made in three sections are shown provided on their lower faces with hooks 8, one end of which is pivotally engaged with the lower face of the middle section of said rail, and the other hook-shaped end 9 detachably engaged with an eye 9' depending from the lower face of the adjacent end section so that these adjacent sections are held 85 rigid in relation to each other when in set up position, the hinge thereof being disposed on the upper face, and would permit these sections to collapse if these hooks or some other means were not provided to prevent this.

The side and end rails are designed to be 95 adjustably connected at the corners of the frame by means of clamps 25, one being shown engaged with each corner of the frame and constructed in the form of a U-shaped member 26, the arms of which are 100 spaced apart a sufficient distance to span the overlapping ends of the side and end rail to which the clamp is to be applied, one of said arms having a flat rail engaging face 27, and the other being apertured and internally threaded to receive an adjusting and clamping bolt 28 such as is ordinarily employed in clamps of this character, said bolt having a clamping face 29 for engaging the rail which it is designed to clamp and at its 110 other end with a head or finger grip 30 whereby the clamp may be tightened or

loosened at the will of the operator. This clamp is of ordinary construction and the peculiar formation thereof constitutes no part of this invention as any other suitable 5 clamp may be substituted therefor if desired.

The grooves 4 in the rails are preferably disposed midway the width of said rails so that the hooks 20 which are strung on the 10 rods mounted therein may swing to one side or the other of the rail. These hooks are constructed as shown clearly in Figs. 1 and 3, being preferably composed of wire, and have eyes 21 formed at one end through 15 which the rods 15 are designed to extend. The shanks 22 of these hooks are made of a sufficient length to span the distance between the rods and the opposed side edges of the rails and to project slightly beyond said 20 edges and are provided at their terminals with laterally extending hooks 23. These hooks are designed for engaging the curtain to be stretched for connecting it to the stretcher, when the device is in use, and 25 when it is not in use these hooks are designed to be swung in the opposite direction with their points or hooked ends engaging the outer edges of the rails in which they are mounted.

30 The outer edges of the upper faces of these rails 1 and 10 are preferably provided with scales shown at 11 to provide for the proper positioning of the rails relatively to each other and for the proper positioning 35 of the hooks on their pivot rods.

From the above description it will be obvious that this stretcher may be readily disassembled and folded in compact form when not in use by simply releasing the corner 40 clamps 25 and removing them from the stretcher. The hooks 8 are then disengaged from their eyes 9 and the sections of the side rails are folded one on the other as will be clearly understood. The end rails are then 45 folded in a similar manner and placed on top or by the side of the folded side rails

and may all be secured together by any suitable fastening element, such as straps, rope or the like (not shown).

To set up the stretcher for use, the operation is reversed, the rails being opened and disposed in the proper position relative to each other with the hooks 8 engaged in their eyes 9 and the clamps 25 engaged with the lapping corners of said rails and the 55 stretcher is then ready for use, the curtain being placed between the rails and engaged with the hooks 20.

From the foregoing description, taken in connection with the accompanying drawing, the advantages of the construction and of the method of operation will be readily apparent to those skilled in the art to which the invention appertains and while I have described the principle of operation of the 65 invention together with the device which I now consider to be the best embodiment thereof, I desire to have it understood that the device shown is merely illustrative and that such changes may be made as are within 70 the scope of the claimed invention.

I claim:

In a curtain stretcher, adjustably and detachably connected end and side rails each composed of sections hingedly connected at 75 their ends, longitudinally extending grooves in one face of said rails, said grooves having undercut side walls, blocks fitting in said grooves to form rod supports and seats, rods of less diameter than said grooves disposed 80 therein and secured to said seats, said rods being made in sections corresponding in length to the length of the rail sections on which they are mounted, and attaching hooks 85 strung on said rods.

In testimony whereof I affix my signature in presence of two witnesses.

LEWIS S. KEIM.
